PORTABLE CONVEYING APPARATUS

Joseph H. Morrow, Hokendauqua, Pa., assignor
to Fuller Company, Catasauqua, Pa., a corpora-
tion of Delaware

Application August 11, 1933, Serial No. 684,643

15 Claims. (Cl. 302—17)

This invention relates to portable apparatus for conveying pulverized or finely divided materials, and more particularly to a conveyor of large capacity adapted for unloading vessels and for re-
claiming materials from warehouses and stock
piles. It is capable, when suspended and
lowered from a boom or crane into the ma-
terials to be conveyed, of cutting its way
through the materials and pumping them through
small diameter pipe lines of extended length and
elevation. The materials which can be conveyed
include Portland cement, pulverized limestone,
lime, soda ash and others having the character-
istic of becoming fluent when mixed with air in
the proper proportions.

The invention is particularly directed to modi-
fications and improvements of the apparatus dis-
closed in my previous Patent No. 1,890,298, and
also to the patents referred to therein. The de-
tails of operation of these conveyors and espe-
cially the pumps are now well-understood in the
art, and are described fully in the patents men-
tioned above.

In brief, the operation of the portable pumping
system is as follows: As the materials lying in
the holds of vessels or other types of storage are
usually inert, as they contain very little entrained
air, they frequently become compacted or lumpy
and will not flow by gravity into the barrel of
the pump. In order that these conditions may
be overcome, and materials carried to the inlet
of a pump barrel at a rate rapid enough to main-
tain the fullest conveying capacity of the appa-
ratus, as well as to insure uniformity in oper-
ation, including the maintenance of the proper
"seal" density, a feeding means must be provided
to break up the compacted materials and bring
them, and preferably force them, into the barrel
of the pump.

In my patent above noted, I have shown a feed-
ing device, including a perforated disc, well
adapted to perform these functions, when the appa-
ratus is supported on wheels to recover cement
from cars, flat-bottom barges or warehouses. The
pulverized materials delivered in a relatively
dense condition by the disc to the barrel of the
pump are engaged by a rapidly rotating impeller
screw. This screw is so arranged that the ma-
terials are compacted as they are advanced
through the barrel to form a "seal" of sufficient
density to resist the escape of air, injected into
the barrel slightly beyond the terminal flight of
the screw backwardly along the flights of the
screw, the density of the seal preferably being
55 maintained at the minimum density permitted by

the back pressure of the system and the inlet
pressure of the air. The purpose of the air so
injected is to aerate or fluidize the material and
aid its conveyance through the pipe-line system.
Various expedients for forming the seal have been
discussed in the patents mentioned above, the most
common being to employ screw flights of decreas-
ing pitch toward the terminal flight, usually in
combination with a space provided between the
terminal flight and the point of air admission.
The aerated material is forced through the pipe
line system by the displacement effect of the im-
peller screw and the normal expansion of the air
used to create the fluent condition.

The conveyor system itself usually comprises
a sufficient length of flexible hose, preferably
reinforced rubber, to allow the pump to be moved
throughout the space in which the material is
stored, the hose being suitably coupled to the
usual steel pipe line through which delivery is
made to the various receiving receptacles.

The present invention is concerned with a
pump of high capacity and capable of trans-
porting material over the long distances fre-
quently encountered between vessels and the stor-
age or warehouse buildings. Thus, it has been
used to advantage for conveying cement from
vessels, previously used for transporting bagged
shipments, and has accordingly provided for a
considerable reduction in the costs of transporta-
tion and handling. The invention is likewise
adapted for recovering cement and other ma-
terials from stockhouses, without danger to
workmen, and without loss of material. As is
well known, the ground level stockhouse is the
cheapest form of storage, but heretofore has had
the decided disadvantage of danger to workmen,
due to slides of material, and no efficient and con-
venient apparatus existed for recovering the
material.

In the initial stages of its operation, the appa-
ratus need not be accompanied by an operator,
but is simply lowered into the material. The
feeding devices permit it to continue to descend
and recover material over a wide area. As oper-
ation proceeds, movement of the apparatus and
vertical cutting or under-cutting by the feeder
causes the material to flow by gravity and bury
the inlet of the pump, thus maintaining a head
of material which assists in keeping the appa-
ratus operating at full capacity.

Final recovery of the material lying in cor-
ners or in small piles on the floor is made first
by guiding the apparatus manually, and later
by sweeping or shovelling the material into piles

so that it can be picked up by the feeding devices. The apparatus is so arranged that it can be buried by slides of material without danger to the parts.

- 5 In general, the new apparatus is similar in arrangement to that disclosed in my patent referred to above. Its construction, however, differs considerably in order to adapt it to the peculiar requirements and use as described. It differs particularly in that the pump barrel, impeller screw and driving motor are arranged for vertical operation, the feeder drive mechanism is preferably located between the motor and the barrel of the pump, and the feeder preferably comprises two discs of a novel type, arranged in planes at right angles to the axis of the screw, the discs spanning a considerably greater area of material than the inlet to the barrel.

As the apparatus is freely suspended, the two feeding discs or their equivalents have approximately equal and opposite reactions to prevent the apparatus from turning. Thus, a single horizontal disc in combination with the vertical pump fails to maintain the desired capacity, will not allow the apparatus to descend vertically, and has a decided disadvantage in causing the apparatus to tend toward rotation about the center of the feed disc, even if a vertical plate is attached to the barrel of the pump to engage the material and resist rotation.

The discs may be provided with cutting edges, and in addition to countersunk perforations, are provided with radial openings, preferably punched or otherwise so formed that the metal is bent downwardly to form scoops or lifters, whereby the discs will tend to cut or bore downwardly and accelerate the movement of material to the inlet of the barrel.

The discs preferably overlap, and sufficient vertical clearance is provided to clear the scoops. Turning oppositely, they deliver and force the material into a hood at the entrance of the barrel where it is engaged by a vertical impeller screw rotating in the usual pump barrel. The usual air ring is provided beyond the terminal flight of the screw and the discharge section includes an angular or offset elbow, to make connection to the flexible section of the transport line.

The screw shaft passes through a wall of the elbow, and is shouldered to receive two bushings, both of which are secured, as by means of keys, so that the bushings turn with the shaft.

Sealing devices for dust and lubricants are provided for the shaft in order to protect the bearings and speed reduction gearing, located above the wall of the elbow. Although a counter-current of air at higher pressure than that of the material and air in the discharge elbow is caused to flow around the shaft and into the elbow, as is usual in pumps of this type, this expedient cannot be relied upon exclusively to protect the bearings, gears and other parts beyond the wall of the elbow, because the apparatus is subjected to rough usage by unskilled and careless operators, and positive seal or "dead end" is desirable to prevent a flow of air upwardly. Accordingly, a chamber is provided in the discharge section to receive a positive dust sealing device arranged on an inner or lower shaft bushing.

This bushing is keyed to the outer or upper bushing so that it can be removed with the dust sealing devices, through a port in the wall of the chamber, for repair or replacement after the shaft has been drawn through it, and without removing the outer bushing or dismantling the

shaft bearing assembly or the speed reduction mechanism. This arrangement effectively protects the parts of the apparatus above the discharge elbow, at the same time enabling the operator to keep the pump in operation with a minimum of delays for repair. This dust sealing apparatus is disclosed in full detail in my co-pending application Serial No. 685,167, filed August 15, 1933.

The screw is driven preferably by an electric motor, ordinarily a squirrel cage induction motor, which may comprise a standard commercial form of vertical stator frame, and a rotor suitably secured to the upper screw bushing, and the frame is provided with end-bells specially made so that the same bearings will serve both for the impeller screw and the motor. The screw shaft is arranged for vertical adjustment within the bushings, whereby the seal of the pump may be changed without disturbing the dynamic balance of the screw, as by cutting away or adding portions of the terminal flight.

In order to accommodate pumps of the same barrel dimensions to various conveying distances, it will be obvious that the apparatus must be accommodated to wide ranges of driving motor sizes. To this end, I prefer to employ a novel type of power take-off and speed reduction mechanism for the feeding discs and to locate this mechanism between the motor and the barrel of the pump. As the feed discs are most efficient at a speed of about 30 R. P. M. and as 900 to 1200 R. P. M. motors are commonly used, reduction gearing of the proper ratio is provided.

By this arrangement, the only substantial changes necessary to construct the apparatus to accommodate various sizes of motors include the proper size of motor end-bells and lengths of the upper screw bushings and screw shafts.

For a more complete understanding of the invention, reference is made to the accompanying drawings, in which

Fig. 1 is a side elevation;

Fig. 2 is an elevation, partly in cross-section, on line 2—2 of Fig. 1;

Fig. 3 is a detail of the feeder drive and speed reduction mechanism on line 3—3 of Fig. 2;

Fig. 4 is a plan view of the feeding discs;

Fig. 5 is a cross-sectional detail of a feeding disc on line 5—5 of Fig. 4, and

Fig. 6 is a cross-sectional detail of the one-way valve and line blow-out device.

Referring first to Fig. 1, the apparatus will be seen to comprise generally, a vertically arranged pump assembly 1, feeder drive mechanism 2, and a driving motor 3, the apparatus being arranged for suspension from a boom or crane (not shown), as indicated generally by the chain block and hook 4. The pump barrel 5, as will be seen in detail in Fig. 2, terminates in a hood 6, opening at the side toward the direction of the incoming material and which spans the inner halves of the feeding discs 7 and 8, which preferably overlap and which span a wide area of material. The material is carried by the discs into the hood, where it is engaged by the lower flight of the impeller screw 9, secured to the screw shaft 10, the lower flight extending below the inlet to the barrel 5. As is well understood, the pitch of the flights preferably decreases toward the terminal flight 11, in order to compact the material and assist in forming the seal. It is likewise well understood that the density of the material to be handled and the back pressure of the system, due

80

150

to the length, diameter, etc., determine the degree of pitch.

In order to avoid excessive friction, and provide for variation in the seal density to suit different operating conditions, I prefer to combine with the differential pitch of the screw the expedient, as referred to in the patents above mentioned, of providing a space between the terminal flight 11 and the point of air admission indicated by the air ring 12, and to make the length of this space variable, as described hereinafter.

The air ring 12 is suitably flanged and secured to the discharge section 13, which includes an offset discharge elbow 14, suitably flanged and secured to the one-way valve and blowout device 15, the details of which are shown more particularly in Fig. 6.

The one-way valve comprises an inlet 16, provided with a seat 17 for a flap valve 18, carried by a shaft 19. The flap valve 18 is free to drop by gravity into closed position, and is maintained in the open position only by the displacement of material against it, whereby if the feed stops or the power fails, material in the vertical section 25 of the system is restrained from flowing backwardly, a condition which might create a dust nuisance, increase the starting torque of the screw and possibly cause dust to enter the orifices of the air ring or enter the parts above the elbow. Beyond the flap valve 18, an inlet 20 is provided for the admission of air in sufficient volume to clear the transport line of material while it is still in an aerated condition, and after the pump has been shut down. The valve 15 is suitably flanged to receive the coupling 21 of the flexible hose 22, through which the material passes to the stationary sections of the pipe line (not shown).

The screw shaft 10 passes upwardly through the wall of the elbow 14 and the upper part of the discharge section 13, and is reduced in diameter forming a shoulder 23 to engage an inner or lower bushing 24 and an outer or upper bushing 25. These bushings are keyed to each other, as at 26, and the upper bushing is keyed to the shaft by the lock collar and key 27.

The usual clearance is provided at 28, between the shaft 11 and the walls of the discharge section 13, to provide a passage for a countercurrent of air, admitted through the usual tubing and choke-plug, as indicated by the arrow in Fig. 2, to resist upward movement of dust.

A chamber 29 is provided in the upper portion of the discharge section 13, in order to accommodate a positive dust sealing device such as that disclosed in my application above identified, and which in this case should preferably comprise a flanged ring 30, which surrounds the shaft bushing 24 and is held stationary by securing its flange to the bottom wall of the chamber 29 by cap-screws. A complementary ring 31 engages the upper wall of the chamber and each is provided with rotating rings such as 32, the rotating rings being held in engagement with the stationary rings 30 and 31 by means of a coil spring 33. The rings 32 rotate with the shaft, due to the presence of suitable packing, usually rubber rings, but it is to be understood that the rotating and fixed rings are in actual metal-to-metal engagement, excepting for the lubricant, preferably a medium oil, with which the chamber 29 should be partially filled.

The surface contact of the rings and the presence of the lubricant prevents damage to the driving parts if air pressure fails, by excluding abra-

sive dusts, and also serves as a "dead end" to prevent upward escape of compressed air carrying dust particles.

The upper end of the discharge section 13 is flanged and secured to the lower half 34 of the feeder drive housing, which is provided with a central chamber 35 to accommodate a sealing device 36 similar to that described above, but having as its main object the function of preventing the escape of lubricant, preferably light fibre grease. The power takeoff and speed reduction mechanism for driving the feed discs comprises a helical gear 37, secured to the upper shaft bushing 25, and as shown in Fig. 3, meshing with gear 38 on the countershaft 39. The countershaft is supported in suitable bearings, as indicated at 40, and carries near its opposite ends worms 41 which drive helical gears 42.

As the remainder of the driving mechanism for the discs 7 and 8 is identical, except for opposite rotation, only one will be described in detail. The helical gear 42 is secured to the upper end of the vertical disc shaft 43, the latter being supported for rotation in a radial bearing 44 in the upper half 45 of the housing, and a radial and thrust bearing 46 in the lower half 34. The lower end of the shaft 43 is suitably supported for rotation in the bushed bearing 47, through which it passes, the disc 8 being secured at its center to the end of the shaft, preferably by soft or light rivets which will shear, if tramp materials are engaged, to prevent injury to the drive mechanism.

The disc connection is provided with an extension 48, below the end surface of the disc, to prevent engagement of the latter with the floor. The bearing 47 is secured to the barrel 5 by a bracket 49, which carries a support 50, preferably formed as an integral part of the casting, a pair of supports 50, or their equivalents being necessary to prevent damage to the feed discs when the pump is out of service and resting on its side; that is, the right of Fig. 1.

The screw shaft bearing arrangement comprises a lower radial bearing 51, carried by the upper half 45 of the housing, and having its inner race abutting the shoulder 52 formed by the enlarged section 53 of the upper shaft bushing 25. As the thrust of the screw is downward, the upper end of the screw is supported in the combined radial and thrust bearing 54, supported by the upper end-bell 55 of the motor 3.

The electrical parts of the motors commonly employed consist of a standard vertical stator frame 56 and rotor 57, the latter being suitably keyed as at 58 to the upper shaft bushing 25. The lower end-bell 59 is, like the end-bell 55, of special construction and is suitably flanged and secured to a complementary flange on the upper half 45 of the speed reducer housing. As the entire mechanism, with the exception of the screw shaft, is supported by the end-bell 59, damaged motors can be repaired or replaced without dismantling the pump, and various sizes of motors can be used with no changes excepting in the length of the screw shaft 10, and bushing 53.

To remove the screw shaft 10, the apparatus may be raised or tilted on its side, the feed discs 7 and 8, the dust cap 62 and the jam nut 63 removed, whereupon the shaft may be drawn downwardly through the bushings and barrel. In order that the distance between the terminal flight 11 and the air ring 12 may be modified without altering the terminal flight, one or more

washers 64 are inserted between the jam nut 63 and the lock collar and key 27. By applying these washers, the shaft 10 may be lifted and the distance between the terminal flight 11 and the air 5 ring 12 decreased, thus reducing the density of the seal. It will be understood that a seal of minimum density is desired to reduce the power to turn the shaft by reducing the friction load, and likewise to decrease wear on the parts. To 10 compensate for the displacement of the shoulder 23 on the shaft with relation to the lower bushing 24, washers 65 are added or removed, the upper washer being preferably of leather, fabric or other packing material to prevent the entrance of dust between the shaft and the bushings.

I have found that the dust sealing apparatus contained in the chamber 29 to be the part most liable to wear, caused by improper pressure reduction in the usual air supply in the space 28 between the shaft and the wall of the discharge section 13. In order that the sealing device may be removed and repaired or a new one substituted without dismantling the apparatus, the operator 25 proceeds as in removing the screw and when the shaft passes the inner bushing 24, the ports 65, shown in Fig. 1, and which communicate with the chamber 29, are opened; the cap-screws or other securing devices which retain the flanged rings 30 and 31 are removed, the spring 33 is compressed, thereby releasing the entire dust seal assembly, including the bushing 24, the assembly being removable through either one of the ports 65.

35 The air supply, from any suitable source (not shown) and ranging in pressures from 5 to 40 pounds, depending upon the quantity of material handled, its density and the distance to which it must be transported, enters through a suitable 40 inlet 66, in the direction of the arrow, under the control of a valve or cock 67. It is preferably piped to both sides of the air ring 12, through suitable branch piping 68, this air ring being of usual design will not be described in detail. 45 Above the valve 67 a branch line 68a under control of valve 69 serves to admit air through the inlet 20, shown in Fig. 6. Air is admitted through the inlet 20 only when the pump is stopped, and is then admitted in large volume 50 while the material is still fluent in order to clear the transport line so that the apparatus can again be started without overloading the pump motor. This is particularly necessary when handling heavy materials such as cement, and 55 when the pump is to be shut down for several hours. For short periods, especially when lighter materials are conveyed, this procedure is desirable, but not absolutely essential.

To assist in the final recovery of material, a 60 railing 70, suitably supported from the barrel 5, and the bearing housings 47, is provided to enable the operator to turn the apparatus and guide the feed discs into the material.

It has been found that the best design of 65 feeding discs is that shown in Figs. 4 and 5. The periphery of each disc is preferably serrated as at 71, and provided with inclined surfaces 72 which serve as plows to assist in undercutting the densely compacted material and to cause it to break up and flow by gravity to the upper surfaces of the discs. In order that the apparatus may bore downwardly into the mass of material, each disc is provided with a plurality of radially punched slots 73, the slots being 70 punched on three sides and the metal bent down-

wardly to form scoops or lifters 74, as shown in Fig. 5. Most of the material loosened by the scoops 74 flows upwardly along their inclined surfaces, and rests upon the discs and the remainder passes through the countersunk circular apertures 75.

The operation of the apparatus will be apparent from the above description, and it will be understood that it is to be suspended from any suitable apparatus from which it can be raised and lowered at will and moved laterally within the vessel or other storage receptacle.

At the beginning of the operation of recovering material, the air is first admitted through the air ring 12, under the control of valve 67. The motor is then started and the apparatus lowered as nearly toward the center of the material as is convenient, as in this location transverse movement of the apparatus is minimized, for unless the material is in an exceptionally dense condition, the material will flow by gravity toward the inlet from all directions. The operator lowers the machine from time to time as the head above the feed discs decreases to a point where there is liability of operation below maximum capacity. For final recovery, the operator first guides the apparatus by means of the hand rail 70 and shovels or sweeps the residue into piles from which it can be picked up by the feed discs.

It will be understood that various modifications may be made in the apparatus, that other types of motors may be used and that the feeding apparatus may be modified or independently driven without departing from the spirit of the invention.

I claim:

1. Conveying apparatus for unloading and reclaiming pulverulent materials and arranged to be suspended and lowered into the materials, comprising the combination of a vertical barrel having an open lower end for the admission of materials, an offset discharge elbow connected to the upper end, a screw shaft arranged concentrically within the barrel, and extending upwardly through a wall of the elbow, an electric motor having its rotor secured to the shaft near its upper end, a feeder for delivering material to the open end of the barrel adjacent thereto, and means for driving the feeder from the shaft, comprising power takeoff and speed reduction gearing, arranged in a housing secured to the frame of the motor, the housing supporting the feeder, barrel and discharge elbow.

2. Conveying apparatus for unloading and reclaiming pulverulent materials, and arranged to be suspended and lowered into the material, comprising the combination of a vertical barrel having an open lower end for the admission of materials, an offset discharge elbow connected to the upper end, a screw shaft arranged concentrically within the barrel and extending upwardly through a wall of the elbow, a motor for driving the shaft secured thereto near its upper end, a feeder adjacent to and below the open end of the barrel comprising at least one horizontal perforated disc, arranged on a substantially vertical driving shaft, and means for driving the feeder at relatively slow speed to deliver material to the open end of the barrel.

3. Conveying apparatus for unloading and reclaiming pulverulent materials, and arranged to be suspended and lowered into the material, comprising the combination of a vertical barrel having an open lower end for the admission of

- material, an offset discharge elbow connected to the upper end, a screw shaft arranged concentrically within the barrel and extending upwardly through a wall of the elbow, a motor for driving the shaft secured thereto near its upper end, a feeder adjacent to the open end of the barrel, comprising at least one substantially horizontal disc provided with openings and scoops extending below the under surface of the disc at one side of the openings, the disc being arranged on a substantially vertical driving shaft, and means for driving the disc.

4. Conveying apparatus for unloading and reclaiming pulverulent materials, and arranged to be suspended and lowered into the material, comprising the combination of a vertical barrel having an open lower end for the admission of material, an offset discharge elbow connected to the upper end, a screw shaft arranged concentrically within the barrel and extending upwardly through a wall of the elbow, a motor for driving the shaft secured thereto near its upper end, a feeder secured to the barrel near the open end thereof, comprising at least one substantially horizontal disc, provided with substantially radial openings, inclined lifters at one side of the openings and extending below the under surface of the disc, the disc being secured at its center to a vertical driving shaft, and means for driving the disc.

5. Conveying apparatus for unloading and reclaiming pulverulent materials, and arranged to be suspended and lowered into the material, comprising the combination of a vertical barrel having an open lower end for the admission of material, an offset discharge elbow connected to the upper end, a screw shaft arranged concentrically within the barrel and extending upwardly through a wall of the elbow, a motor for driving the shaft secured thereto near its upper end, a feeder secured to the barrel near the open end thereof, comprising at least one substantially horizontal disc, having a serrated periphery and provided with substantially radial openings, inclined lifters at one side of the openings and extending below the under surface of the disc, the disc being secured at its center to a vertical driving shaft, and means for driving the disc.

6. Conveying apparatus for unloading and reclaiming pulverulent materials, and arranged to be suspended and lowered into the material, comprising the combination of a vertical barrel having an open lower end for the admission of material, an offset discharge elbow connected to the upper end, a screw shaft arranged concentrically within the barrel and extending upwardly through a wall of the elbow, means for driving the shaft connected thereto near its upper end, a feeder adjacent to and below the open end of the barrel, comprising a pair of perforated, substantially horizontal feed discs, and means for driving the discs at a speed considerably lower than the speed of the shaft.

7. Conveying apparatus for unloading and reclaiming pulverulent materials, and arranged to be suspended and lowered into the material, comprising the combination of a vertical barrel, having an open lower end for the admission of material, an offset discharge elbow connected to the upper end, a screw shaft arranged concentrically within the barrel and extending upwardly through a wall of the elbow, means for driving the shaft connected thereto near its upper end, a feeder adjacent to and below the open end of the barrel, comprising a pair of overlapping, perfo-

rated, substantially horizontal discs, secured at their centers to vertical driving shafts, and means for driving the discs at a speed lower than the speed of the screw shaft.

8. Conveying apparatus for unloading and reclaiming pulverulent materials, and arranged to be suspended and lowered into the material, comprising the combination of a vertical barrel having an open lower end for the admission of materials, an offset discharge elbow connected to the upper end, a screw shaft arranged concentrically within the barrel and extending upwardly through a wall of the elbow, means for driving the shaft secured thereto near its upper end, two perforated, horizontal feed discs, overlapping below the open end of the barrel to deliver material thereto, the discs being secured at their centers to vertical driving shafts, and means for driving the discs.

9. Conveying apparatus for unloading and reclaiming pulverulent materials, and arranged to be suspended and lowered into the material, comprising the combination of a vertical barrel having an open lower end terminating in a hood having an open side for the admission of material, an offset discharge elbow connected to the upper end, a screw shaft arranged concentrically within the barrel, and having a lower flight extending into the hood, the shaft extending upwardly through a wall of the elbow, means for driving the shaft secured thereto near its upper end, a pair of perforated horizontal feed discs overlapping below the hood, the latter spanning substantially the inner halves of the discs, the discs being secured at their centers to vertical driving shafts, and means for driving the discs at a speed considerably slower than that of the screw shaft.

10. Conveying apparatus for unloading and reclaiming pulverulent materials, and arranged to be suspended and lowered into the material, comprising the combination of a vertical barrel having an open lower end terminating in a hood having an open side for the admission of material, an offset discharge elbow connected to the upper end, a screw shaft arranged concentrically within the barrel, and having a lower flight extending into the hood, the shaft extending upwardly through a wall of the elbow, means for driving the shaft secured thereto near its upper end, a pair of perforated horizontal feed discs overlapping below the hood, the latter spanning substantially the inner halves of the discs, the discs being secured at their centers to vertical driving shafts, and means for driving the discs at a speed considerably slower than that of the screw shaft.

11. Conveying apparatus for unloading and reclaiming pulverulent materials, and arranged to be suspended and lowered into the material, comprising the combination of a vertical barrel having an open lower end for the admission of material, an offset discharge elbow connected to the upper end, a screw shaft arranged concentrically within the barrel, and extending upwardly through a wall of the elbow, an electric motor having its rotor secured to its shaft near its upper end, and its stator frame serving to support the entire apparatus, a pair of horizontal feed discs below the open end of the barrel for delivering material thereto, the discs being secured to vertical shafts, and means for driving the shafts from the screw shaft, comprising power take-off and speed reduction gearing, arranged in a housing

connected to and supported by the frame of the motor.

12. In an apparatus for unloading and reclaiming pulverized materials, a feeder comprising the combination of a substantially vertical shaft, means for driving the shaft connected thereto near its upper end, a substantially horizontal feed disc secured at its center to the shaft, the disc being provided with a plurality of perforations and scoops adjacent to at least some of the perforations and extending below the under surface of the disc, the scoops inclining toward the direction of rotation of the disc.

13. Conveying apparatus for pulverulent materials adapted to be suspended and lowered into the material, which comprises a barrel having an open end for the admission of material, a discharge elbow connected to the other end of the barrel, a shaft within the barrel and extending through the wall of the elbow, said shaft carrying screw flights, a shaft mounted outside the barrel and parallel to the shaft therein, a feeder element on said outside shaft, said element being formed to deliver material into the open end of the barrel, means for driving the shafts at different speeds, and means connected to said barrel by which said apparatus may be suspended with said shafts substantially vertical.

14. Conveying apparatus for pulverulent materials adapted to be suspended and lowered into said materials, which comprises a barrel having an inlet and an outlet, a shaft within said barrel

having screw flights for discharging materials through said outlet, a shaft mounted in bearings outside the barrel and lying parallel to the shaft inside the barrel, a feeder element on said outside shaft operable to supply materials to the inside of the barrel through the inlet, a motor attached to the barrel, connections between the motor and shafts, and means connected to the motor by which said apparatus may be suspended with said shafts substantially vertical and said inlet below said outlet.

15. Conveying apparatus for unloading and conveying pulverulent materials, adapted to be suspended and lowered into the materials, comprising the combination of a vertical barrel having an open lower end for the admission of materials, an offset discharge elbow connected to the upper end, a screw shaft having screw flights arranged concentrically within the barrel, the shaft extending upwardly through a wall of the elbow and supported in bearings beyond the wall, a motor for driving the shaft at relatively high speed connected thereto near its upper end, a feeder adjacent to and below the open end of the barrel for delivering material thereto, the feeder spanning a greater area of material than the barrel, means for driving the feeder at relatively slow speed, and means by which said apparatus may be suspended with the screw shaft substantially vertical.
